(57) **CLAIM**

The ornamental design for an adjustable floor lamp, as shown and described.

DESCRIPTION

FIG. 1 is a perspective view of an adjustable floor lamp showing the claimed design, the floor lamp including a base, a first arm having a first portion pivotally coupled to the base and a second portion pivotally coupled to a second arm, which is in turn pivotally coupled to a third arm having a light source.

The first arm's first portion is coupled to the first arm's second portion such that the second portion is rotatable relative to the first portion from a flush position (FIG. 8) to a rotated position (FIGS. 1-7).

FIG. 2 is a perspective view thereof with the second portion in the rotated position;

FIG. 3 is a front view thereof with the second portion in the rotated position;

FIG. 4 is a rear view thereof with the second portion in the rotated position;

FIG. 5 is a right side view thereof with the second portion in the rotated position;

FIG. 6 is a left side view thereof with the second portion in the rotated position;

FIG. 7 is a top view thereof with the second portion in the rotated position; and,

FIG. 8 is a front perspective view thereof with the second portion in the flush position.

The claimed design extends to—but does not include—the dash-dot boundary lines drawn around the first arm, the second arm, and the third arm.

The dashed lines in the figures form no part of the claimed designs. Surface shading in the figures is provided solely to indicate contour. The surfaces or portions of the adjustable floor lamp not shown in the figures or otherwise described in the specification form no part of the claimed design.

1 Claim, 7 Drawing Sheets
